UNITED STATES PATENT OFFICE.

VOJTECH PUC, OF PRAGUE-VINOHRADY, CZECHOSLOVAKIA.

SAFETY PIN.

Application filed January 26, 1926, Serial No. 83,983, and in Czechoslovakia January 31, 1925.

In order to prevent the pinned material from passing from the pointed shank of the pin to the shank carrying the closing caps, the bridge between these parts has been provided with a guard or enlargement, which usually consists of a metal piece, soldered to it. The manufacturing of such safety-pins requires a circumstantial work. It has been also proposed (see American Patents 875, 10 094 and 908,693) to press the metal piece on the bridge, but hitherto this metal piece surrounds too the parts of the shanks abutting on the bridge. Thus it is possible, that the pinned material get pinched between the metal piece and the shanks of the safety-pin, especially when a gaping results by using the pin for some time.

The present invention consists in pressing the guard or metal piece on the bridge only 20 so that the abutting parts of the shanks of the pin remain free whereby the bridge is formed with a profile in length or in cross-section so that an enlargement firmly fixed to the bridge is obtained, as desired.

The drawing shows several constructions 25 of a pin in accordance with my invention, by way of example. Fig. 1 shows an outline of the metal piece to be pressed on the bridge, Fig. 2 shows an outline of the open safety pin without the enlargement, Fig. 3 shows the closed safety-pin fitted with the enlargement piece, the latter being shown in section, Fig. 4 shows a modified form of the safety pin with the enlargement piece in section, Fig. 5 another modified form of the bridge-end-part of the safety pin with the enlargement piece in section, Fig. 6 is a cross section on line $x-x$ of Fig. 5 and Fig. 7 is a modified form of the bridge-end-part of

the safety pin with the enlargement piece in section.

The blunt shank 1 of the safety pin is connected by means of the bridge 3 with the pointed shank 2.

In accordance with this invention the bridge 3 is provided with a bulging part 4 (see Figs. 2 and 3). By pressing the piece of tin 5 about the bridge 3 the desired enlargement is obtained, its connection with the bridge being quite firm and permanent.

The same effect may be obtained if in accordance with Fig. 4 the bridge 3' is somewhat bent out, whereas the walls of the inner hollow space of the enlargement piece 5 remain straight.

Another modified form is shown in Figs. 5 and 6 which consists in making the surface of the bridge 3'' flat.

And another modified form of adjusting the bridge for the said purpose may be that shown in Fig. 7. In this modified construction the bridge 3''' is provided with notches 8 in which the material of the enlargement piece 5 is embedded when pressed about the bridge.

What I claim to be new is:

1. A safety pin comprising a bridge connecting the shanks of the pin, and a guard pressed around the bridge and spaced from the said shanks.

2. A safety pin comprising a bridge connecting the shanks of the pin, and a guard rigidly secured to the bridge and spaced from the said shanks.

In testimony whereof I affix my signature.

VOJTECH PUC.
